(57) **CLAIM**

The ornamental design for a protective casing for electrical devices, as shown and described.

DESCRIPTION

FIG. 1 is a perspective view of a protective casing for electrical devices showing our new design;

FIG. 2 is a right side elevation view thereof;

FIG. 3 is a left side elevation view thereof;

FIG. 4 is a front elevation view thereof;

FIG. 5 is a rear elevation view thereof; and,

FIG. 6 is a top plan view thereof.

The broken line portion of the figure drawings is included to show unclaimed subject matter only and forms no part of the claimed design.
